RECORD PLAYER HOUSING

Harvey K. McQuarrie, Kitchener, Ontario, Canada, assignor to Electrohome Limited, Kitchener, Ontario, Canada

Filed Feb. 23, 1973, Ser. No. 335,032

Term of patent 14 years

Int. Cl. D14—01
U.S. Cl. D56—4 R

FIG. 1

FIG. 2

FIG. 3

FIG. 4

FIG. 1 is an elevational view of a record player housing showing my new design;

FIG. 2 is a top plan view;

FIG. 3 is a bottom plan view; and

FIG. 4 is an enlarged scale perspective view of a fragmentary portion of the tambour ornamentation band of FIG. 1.

I claim:

The ornamental design for a record player housing, as shown and described.
